Ohio

Filed Dec. 13, 1971, Ser. No. 207,728

Term of patent 14 years

Int. Cl. D10—05

U.S. Cl. D26—1 Q

FIG. 1 is a perspective view of an elongated hand held electrical test probe embodying our design;

FIG. 2 is a side elevational view thereof;

FIG. 3 is a top plan view thereof;

FIG. 4 is a bottom plan view thereof;

FIG. 5 is a front elevational view thereof; and

FIG. 6 is an end view thereof.

The side opposite from that shown in FIG. 2 is identical thereto and, hence, only one side view is illustrated.

We claim:

The ornamental design for an elongated hand held electrical test probe, substantially as shown and described.
